UNITED STATES PATENT OFFICE.

EDWARD J. RICE, OF ROCHESTER, NEW YORK, ASSIGNOR TO JAMES E. RICE, OF SAME PLACE.

DESIGN FOR A FLANGE FOR CLOSET-BENDS.

SPECIFICATION forming part of Design No. 29,291, dated August 30, 1898.

Application filed August 8, 1898. Serial No. 688,118. Term of patent 14 years.

To all whom it may concern:

Be it known that I, EDWARD J. RICE, a citizen of the United States, residing at Rochester, in the county of Monroe and State of New York, have invented a certain new and useful Design for a Threaded Flange for Closet Bends and Ferrules; and I do declare the following to be a full, clear, and exact description of the invention, such as will enable others skilled in the art to which it appertains to make and use the same, reference being had to the accompanying drawings, which form a part of this specification.

This invention relates to a certain new and useful design for waste-pipe connections, and especially to a flange which is threaded and designed for connection to closet-bend ferrules, the flange having a series of elongated and curved slots and a central aperture.

My flanged connection is clearly illustrated in the accompanying drawings, in which—

Figure 1 is a top plan view of the flange, showing the shape of the slots therein; and Fig. 2 is a side elevation of the same.

My design consists in the flange, which is circular in outline and having a series of elongated slots therein, which slots are longitudinally curved and terminate at corresponding ends in slightly-enlarged circular-outlined spaces. In the center of the flange is a circular-outlined aperture. On the under side of the flange is a shoulder circular [in outline and extending about the central aperture in the flange. This shoulder merges into a contracted portion, which has about its outer circumference spirally-arranged threads.

Having thus described my invention, what I claim is—

The design for a flange for closet bend and ferrule, substantially as shown and described.

In testimony whereof I affix my signature in presence of two witnesses.

EDWARD J. RICE.
